UNITED STATES PATENT OFFICE.

MICHAEL WEINER, OF CLEVELAND, OHIO, ASSIGNOR TO BAILEY & WHITMORE, OF SAME PLACE.

RUFFLER FOR SEWING-MACHINES.

SPECIFICATION forming part of Letters Patent No. 251,808, dated January 3, 1882.

Application filed April 5, 1881. (Model.)

To all whom it may concern:

Be it known that I, MICHAEL WEINER, of Cleveland, in the county of Cuyahoga and State of Ohio, have invented certain new and useful 5 Improvements in Rufflers for Sewing-Machines; and I do hereby declare the following to be a full, clear, and exact description of the invention, such as will enable others skilled in the art to which it pertains to make and use it, reference 10 to being had to the accompanying drawings, which form part of this specification.

My invention relates to gathering and ruffling attachments for sewing-machines in which the cloth is gathered by a reciprocating blade 15 which may be actuated by means of the needle-bar, as shown in the drawings, or in any other suitable manner, and also in which the ruffling attachment is secured to a presser foot.

My invention relates to rufflers so constructed 20 that one piece of goods may be ruffled or gathered and either one or two pieces sewed to it at the same time. When it is desired to sew two other pieces to the piece to be ruffled, one piece may be sewed to the under and one to 25 the upper side of the same, all at one and the same time that the center piece is being ruffled, the said upper and lower piece, or both, being stitched on the right side of the goods and finished without the necessity of passing 30 the goods through the machine a second time.

It consists in providing an adjustable guide whereby the upper piece may be stitched nearer to or farther from its edge, said guide operating in a slot which is cut in the presser-foot in 35 such a manner as to admit a piece of goods, or, where it is desired to use cordings, (usually another piece of goods of some bright and different shade, which is sewed between the ruffle and the upper piece, its edge only protruding,) the two may pass through said slot.

It further consists in providing guides for the piece to be ruffled and for the under piece, the same being separate from the ruffler proper, and attached either to the needle-plate, as shown 45 in the drawings, or it may be attached to any suitable part of the base. To this guide is fastened (or it may be made part of it) a guard-spring, which keeps the piece to be ruffled from being operated upon by the feed of the sewing-machine.

In the drawings, Figure 1 is an isometric view of my ruffler, showing the manner of attaching the same to a sewing-machine. Fig. 2 is a rear view of my ruffler, showing the mechanism for operating the same. Fig. 3 is a longitudinal vertical section of my ruffler and the needle-plate of a sewing-machine, showing more clearly the adjustable guide, and also the guard and ruffle-guide attached to the needle-plate. Fig. 4 is an isometric view of a needle-plate having attached to it the ruffle-guard and guides. Fig. 5 is a transverse section of my ruffler, showing more clearly the slot in the presser-foot and the manner of adjusting the guide therein. Fig. 6 is a detail view of the slotted presser-foot and its guide.

A is the face of a sewing-machine, in which work the needle bar B and presser bar C.

D is the base-plate of a sewing-machine, to which is attached the needle-plate E and feed F, which passes through an opening in said needle-plate.

G is a presser-foot, which is attached to the presser-bar C in the usual manner. To the presser-foot G is attached the ruffler H, the ruffling-blade of which may be operated in the same manner as what is known as the "Johnson Ruffler," and shown in Fig. 2 of the drawings, a slotted lever being connected at one end to the needle-bar of the machine, while its opposite end is pivoted to the ruffler and provided with an arm, which abuts against lugs on the sliding plate of the ruffler and reciprocates the latter.

a is the reciprocating or ruffling blade, which is provided at its end with teeth, which act to catch the piece of cloth to be ruffled or push it forward. Directly under the blade a is a spring-guard, b, which acts to keep the feed of the machine from operating on the piece of goods to be ruffled, and also to keep said piece in contact with the ruffling-blade a. This spring-guard b is provided at its one end with guides, which may be made, as shown in the drawings, S-shaped, and attached to the said guard in any suitable manner, or it may be made part of the same. This guard b and its guides c are shown attached to the needle-plate E; but it is obvious that the same may be attached in any suitable manner to the base-plate D, the

object being to have it separate from the ruffler H, but attached to the machine in such a manner that it will remain in position when the ruffler is raised by means of the presser-bar, and thus facilitate the adjustment of the goods to be operated upon.

d is a slot which is cut diagonally across the forward lower end of the presser-foot G, and which serves as a guide for any goods that it 10 may be desired to sew to the upper or right side of the ruffle. This slot is provided with an adjustable spring-guide, e, which is operated by means of a set-screw, i, and which serves to guide the edge of the said upper piece to 15 the needle, thus making the stitch nearer to or farther from the edge.

The upper and lower piece of goods are not operated upon by the ruffling-blade a, but are operated upon and pulled forward by means 20 of the feed F, the projection on the rear end of the presser-foot G serving to keep the under piece in contact with the said feed F.

It is obvious that the guard-spring and guide may be secured to the shuttle-slide.

25 It will also be noticed that the guard-spring is raised a short distance above the feed F. My

reason for doing this is to prevent the feed from coming in contact with said guard and either cutting said guard or blunting the teeth of the feed.

30

What I claim is—

1. The combination, with the ruffling-blade and the needle-plate, of a guard-spring secured below said blade so that the latter may bear thereon, and provided at its outer end with 35 strips or arms bent parallel with the end of the spring, one above and one below the same, to form guides, the under strip being secured to the needle-plate, substantially as set forth.

2. The combination, with a presser-foot provided with an inclined slot, of an adjustable spring-guide, e, one end of which is secured to the ruffler, while the other end extends into the slot of the presser-foot, as and for the purpose set forth.

40

In testimony whereof I have signed my name to this specification in the presence of two subscribing witnesses.

MICHAEL WEINER.
